ROBERT J. MILLER
ATTORNEY

UNITED STATES PATENT OFFICE

HERMAN J. HAMMERLY, OF NEW BRITAIN, CONNECTICUT, ASSIGNOR TO THE TRUMBULL ELECTRIC MANUFACTURING COMPANY, OF PLAINVILLE, CONNECTICUT, A CORPORATION OF CONNECTICUT

ELECTRIC SWITCH

Application filed August 6, 1932. Serial No. 627,692.

My invention relates to electric switches and particularly to the type commonly known as safety or enclosed switches.

The main object of my invention is to provide an unusually compact, durable and reliable construction.

Another object is to provide such a construction which can be made and assembled at a minimum of cost.

Another object is to provide a construction of this character in which the switch parts are fully protected against accidental contact when the box is open.

Another object is to provide a construction which can be readily operated with a snap action without danger of sticking or arcing.

Another object is to provide a construction of this character which may be built up of units so as to operate one, two, three or more poles of a circuit in a single box.

Another object is to provide a switch unit which can be readily inserted in a box or removed therefrom independently of the other switch units and without disturbing the operating crank.

Another object is to provide a construction in which the quick-make and break or snap action mechanism may be assembled in the box and tested after which the remaining contact carrying or fuse supporting blocks may be inserted without disturbing the operating mechanism.

Another object is to provide a construction of this character in which the protecting fuses are readily accessible for insertion or removal.

In carrying out the invention the circuit terminals are supported by a number of insulating blocks mounted in a suitable box or receptacle. These blocks are arranged in pairs which also usually carry fuse clips or terminals. One of the blocks carries concealed switch contacts and a switch operating slide which travels through a perforation or passage which extends approximately through the center of the block in a direction parallel with the bottom of the box. An operating crank shaft is mounted in the opposite sides of the box between the respective

pairs of blocks and is detachably connected to the switch slide. The fuses are supported in the fuse terminals in front of or above the crank shaft where they are readily accessible for insertion and removal.

55

Fig. 1 is a front view of a switch embodying my invention, parts of one unit being shown in section and the cover of the box being open and partly broken away.

60

Fig. 2 is a partial horizontal section and end view of the construction shown in Fig. 1.

Fig. 3 is an end view of one of the switch blocks.

Fig. 4 is a vertical sectional view of one of the switch units showing it connected to a fragment of the supporting box.

65

Fig. 5 is a perspective view showing the insulating switch supporting block, the insulating slide and some of the metal parts of one of the switch units.

70

Fig. 6 is a sectional view showing the method of supporting one of the switch contacts.

Fig. 7 is a perspective view of insulating blocks for supporting the lower ends of the fuses and the associated load terminals.

75

The circuit terminals 7 and 8 of each pole of the switch are supported respectively by the insulating blocks 9 and 10, which are mounted in a suitable box or receptacle 11. The fuses 12 are mounted in front of or above the switch blocks and a crank shaft 13 is mounted between the respective pairs of insulating blocks. Any suitable form of actuating mechanism may be employed, such, for instance, as the external handle 14 and snap action or quick-make and break mechanism 15 which is described in detail in my Patent No. 1,838,020, Serial No. 335,250 which issued December 22, 1931.

80

The switch block 9 is detachably mounted in the box, being secured to the back of the box by anchorage screws 16 and 17 which pass through slotted lugs 18 and 19, thus permitting a considerable amount of adjustment of the supporting block with respect to the box, the crank shaft 13 and the adjacent switch blocks.

85

Each switch unit has the spring contact arms 20 and 21 and the contact roller 22. The latter is loosely mounted in an aperture 100

in the insulating plate or slide 23. The stationary contacts are preferably in the form of brackets or elbows and are mounted in recesses 24 and 25 in the block 9. The contact 20 is secured in place by a screw 26 which electrically connects it to one arm of an angle plate 27. The other arm of this plate 27 extends through the insulating block from the recess 24 to a point beneath the terminal 7 which is secured to the arm by the anchorage screw 28. The nut 28' coacts with the screw 28 to hold the terminal 7 and the plate 27 in place. The contact 21 is secured by a screw 29 which also clamps it to the angle plate 30. The arm 30 of this angle plate extends over the upper surface of the block 9 and forms a support for the fuse terminal 31 to which it is secured by the screw 32. The base is provided at each end with projecting lugs having open ended slots such as 33 for the screws 28 and 32.

The block 9 is provided with a passage-way 34 which extends entirely through the block for supporting and guiding the insulating slide 23. The central part of this passage 34 is widened or enlarged to form grooves 35 to permit the travel of the switch contact roller 22. The roller 22 loosely fits in the perforation 36 in the sliding plate and is confined in the groove 35 where it is permitted to travel between the contacts 20 and 21 from the "on" position shown in Fig. 1 to the "off" position shown in Fig. 4. The slide 23 is also provided with a slot 37 which is opened toward the rear so as to facilitate its readily detachable connection with the crank shaft 13.

The fuse clip or terminal 31 is described in detail in my Patent No. 1,851,249, Serial No. 501,779 which issued March 29, 1932.

The fuse terminal 38 is arranged to pair with a similar terminal 31 and is secured in any suitable manner to the terminal 8 so that a fuse may be mounted in any suitable manner to complete the circuit from the terminal 7 through the angle plate 27, switch contact 20 and switch contact roller 22, contact 21, angle plate 30, fuse terminal 31, fuse 12 and fuse terminal 38 to terminal 8.

The terminals along the upper end of the base and which are the line terminals are preferably guarded by means of an insulating fibre strip 40 which is secured by one or more screws 41, which screw into the nuts 28'. This guard strip prevents accidental contact with the terminals and at the same time, being removable, permits access to the terminals for wiring purposes.

I also preferably provide a guard plate 42 of insulating material which is provided with passages for the insulating slides 23 and is mounted beneath the pairs of switch contacts so as to substantially close the recesses 24 and 25 beneath the switch contacts when the switch is being operated to break the circuit.

This plate 42 thus serves to guard the switch contacts on the lower side, and thus prevent any arc from jumping from the contacts to the operating crank.

The operating crank 13 preferably has its ends 43 and 44 pivotally mounted in opposite sides of the box and may be provided with stops 45 and 46 to limit its operating movement.

It will be seen from the foregoing that each switch unit is complete in itself and that it may be inserted in or removed from the box independently of other switch units and without disturbing the crank shaft 13. The shape of the contacts 20 and 21 is such as to provide an effective engagement with the roller 22 and the roller being loosely carried by the slide 23 readily adapts itself to a position of perfect electrical contact with both of the members 20 and 21. The upper ends of the contacts 20 and 21 being bowed outwardly slightly as shown in Figs. 1 and 5, the spring action tends to throw the roller upwardly as the circuit is being opened so as to hasten the breaking of the circuit.

It will also be seen from Fig. 1 that as the circuit is broken the contact roller moves into the groove 35 where it is completely housed, thus completely snuffing out any arc which might otherwise tend to form. There is, of course, a certain amount of clearance in the passage 34 and groove 35 which allows for some circulation of air which is occasioned by the movement of the slide or plunger 23.

The insulating support block 10 for the load terminals may be mounted on a bracket 47 secured by screws 48. The blocks 50 may be in one piece or might be made of a number of sections to correspond with the number of switch blocks 9. The bracket 47 may be secured to the casing by screws 48' or by spot welding.

In Fig. 7 is illustrated a form in which the lower terminal block is made of sections such as 50, each having, for instance, offset joints 51, 52 and fastened to the bridge strip 47 by the usual screws (not shown) passing through the holes 53.

One of these sections 50 is provided to correspond with each switch block and will support the usual fuse terminal and load terminal as shown in Fig. 1.

Block 9 is provided at each of its opposite ends with a projecting lug like 19, each lug having an open-ended slot like 33; the perforation or passage 34 for the insulating slide extends entirely through the block and particular attention is called to the fact that the lugs 19, the slot 33, the passage 34 and all of the remaining passages, holes, recesses, slots, projections are so designed that the completely formed block may be molded by a single, simple, straight movement of the parts of the mold in a direction in line with the passage 34.

It will be noted that the stationary switch

contacts and the movable switching members are located underneath the fuses and their terminals and that the line and load side wire terminals are offset at one side of the fuse 5 terminals and thus it is possible to construct a fused switch which is no greater in length or width dimensions than would be required for a no-switch fuse block having the same capacity or number of poles.

10 By reason of being supported between the switch blocks 9 and the fuse terminal supporting block 10 (or blocks 50), substantially the entire bodies of the fuses are supported in air, relatively far away from metal parts 15 and are therefore much less likely to cause any damage should they blow out on short circuit.

I claim:

1. An electric switch including a box, an 20 actuating crank shaft pivoted in opposite sides of the box, an insulating block mounted in the box at one side of the crank shaft and a second block mounted in the box at the opposite side of the crank shaft, one of said blocks 25 having a passage extending through it at right angles to the crank shaft and a contact chamber at one end of said passage, a stationary contact mounted within said chamber at each side of said passage, an insulating plate 30 slideable in said passage and carrying a switch member adapted to connect said contacts, said plate having a slot open at one edge in which said crank shaft loosely fits, means for actuating said crank shaft and the associated 35 switch member, each block having a fuse clip mounted thereon and a fuse mounted in said clips and extending over the crank shaft between the blocks.

2. An electric switch including a box, an 40 actuating crank shaft pivoted in the box, an insulating block mounted in the box at one side of the crank shaft and a second block mounted in the box at the opposite side of the crank shaft, one of said blocks having a passage 45 extending through it at right angles to the crank shaft, a contact mounted on said block at each side of said passage, an insulating plate slideable in said passage and loosely carrying a switch member adapted to connect 50 said contacts, said plate being connected to said crank shaft, means for actuating said crank shaft and the associated switch member, each block having a fuse clip mounted thereon for supporting a fuse over the crank shaft said blocks being independently removable from the box with their respective attached parts.

3. An electric switch device including a 55 one-piece insulating body having a passage extending therethrough with a recess on each side at one end thereof, a stationary contact at each side of the passage in one of the recesses and having an anchorage foot extending substantially at right angles to the length of said passage, an angle member having one

end secured to the foot of one contact and its other end connected to a circuit terminal, a second angle member having one end secured to the foot of the other contact and having one of its ends in a plane above the plane of 70 said terminal each end of each angle member being secured to said body and a fuse clip connected to the raised end and a switch member 75 slideable in said passage to make and break the circuit in the passage between said stationary contacts.

4. An electric switch device including a one-piece insulating body having a passage extending therethrough with a recess on each side at one end thereof, a stationary contact 80 at each side of the passage in one of the recesses and having an anchorage foot extending substantially at right angles to the length of said passage, an angle member having one end secured to the foot of one contact and its other end connected to a circuit terminal, a second angle member having one end secured to the foot of the other contact, a switch member 85 slideable in said passage to make and break the circuit in the passage between said contacts and an insulating guard for closing the recesses adjacent the contacts and through which a part of the switch member is movable.

5. An electric switch device including a one-piece insulating body having a passage extending therethrough with a recess at each side of one end thereof, a stationary contact at each side of the passage in one of the recesses and having an anchorage foot extending 90 at an angle to the length of said passage, an angle member having one end secured to the foot of one contact and its other end connected to a circuit terminal, a second angle member having one end secured to the foot of the other contact, a fuse clip connected to the other end and a switch member 95 slideable in said passage between said contacts and an insulating guard plate secured to the end of the body for protecting the circuit terminal 100 said body forming the sole means for supporting and guiding said switch member.

6. A switch unit including a one-piece insulating block having a supporting lug at each end with a slot opening toward the end, a terminal recess and a fuse clip anchorage recess opening at one end, contact-receiving recesses open toward the opposite end of said block, a guide passage extending entirely through the block and communicating with the contact-receiving recesses and for housing and guiding the movable switch member and passages extending through the block parallel to the guide passage for receiving the anchorage screws for securing the contacts in place.

7. A switch unit including a one-piece insulating block, having a terminal recess and a fuse clip anchorage recess opening at one end, contact-receiving recesses open toward the other end of said block, a guide passage 115 120 125 130

extending entirely through the block and communicating with the contact-receiving recesses and for housing and guiding the movable switch member and passages extending 5 through the block parallel to the guide passage for receiving the contact anchorage screws and a passage extending through the block from the terminal recess to one of the contact-receiving recesses.

10 8. A switch unit including an insulating block having open recesses in its opposite ends and having a guide passage extending through the block, a circuit terminal secured in the recess in one end of the block, stationary 15 contacts housed in the recesses in the other end of the block on opposite sides of the guide passage, an insulating slide having its edges guided in said passage and a freely rotatable switch contact loosely supported by said slide 20 and movable between said spring contacts.

9. An electric switch construction including an insulating body having a guide passage extending entirely therethrough with a recess on each side of one end thereof, a 25 contact at each side of the passage in one of the recesses and having an anchorage foot extending transversely to the length of said passage, an angle member having one end secured to the foot of one contact and its 30 other end extending to one end of the body, a circuit terminal secured to said extending end, a second angle member having one end secured to the foot of the other contact and a fuse clip connected to its other end, a 35 switch member slideable in said passage between said contacts, a second fuse clip spaced away from and in line with said first mentioned fuse clip and a crank shaft extending across the interior of the box between the fuse 40 clips and connected to said switch member.

10. An electric switch including a box, an actuating crank shaft pivoted in the box, an insulating block mounted in the box at one side of the crank shaft and a second insulating block mounted in the box at the opposite side of the crank shaft, one of said blocks having a guide passage extending entirely through it, a contact mounted in one end of said block at each side of said passage, an insulating plate slideable in said passage and carrying a freely rotatable switch member 50 adapted to connect said contacts, said plate being loosely connected to said crank shaft and quick-break means for actuating said 55 crank shaft and the associated switch member.

11. A switch unit including an insulating body having a vertical passage extending therethrough, a contact housed in the lower 60 end of the body at each side of said passage, a circuit terminal housed in the upper edge of the body and connected to one contact inside of the body, a fuse support mounted on the outer face of the body and connected 65 to the other contact, an insulating slide guid-

ed in said passage and having a loosely mounted and freely rotatable switch member for interposition between said contacts, an insulating guard plate for the circuit terminal on the upper end of the body and an insulating guard plate beneath the contacts.

12. An electric switch including a box, an actuating crank shaft pivoted in opposite sides of the box, an insulating block mounted in the box above the crank shaft and a second block mounted in the box below the crank shaft, one of said blocks having a passage extending through it at right angles to the crank shaft, a spring contact mounted in said block on each side of said passage, an insulating plate slideable in said passage and carrying a switch member adapted to connect said contacts, said plate having a slot open at one end in which said crank shaft loosely fits, means for actuating said crank shaft and the associated switch member with a snap action, each block having a fuse clip and a fuse mounted in said clips and extending over the crank shaft between the blocks.
